his Attorney.

UNITED STATES PATENT OFFICE.

JOHN PETTY, OF LEBANON, PENNSYLVANIA, ASSIGNOR TO JO PET, INC., OF LEBANON, PENNSYLVANIA, A CORPORATION OF PENNSYLVANIA.

SOOT BLOWER.

Application filed August 9, 1923. Serial No. 656,529.

My invention relates to soot blowers especially adapted and intended for use with fire tube boilers. In another application filed by me May 19, 1923, Serial Number 640,189, I have described and shown a soot blower construction especially adapted for use in fire tube boilers in which the tubes are separated by vertical spaces into tube banks. My present invention is especially intended 10 for use with fire tube boilers in which no such separation of the tubes into banks is provided for, although it will be understood that it is also capable of use with such divided banks of tubes. The object of my 15 invention is to provide a soot blower construction comprising a series of soot blower frames each adapted to operate in connection with a separate group of tubes and each being made capable, by means of my 20 novel construction, of being swung away from its operative position in front of the tubes to a position in which it no longer faces the tubes but leaves them free for cleaning, replacement, etc.

25 The nature of my improvements will be best understood as described in connection with the drawings in which:

Figure 1 is a front view of a boiler provided with my improved soot blowing construction.

30 Figure 2 is a side view of the head of the boiler and the soot blower construction.

Figure 3, a plan view taken as on the section line 3—3 of Fig. 1, and

35 Figure 4 a sectional view on the line 4—4 of Fig. 3.

Figure 5 is a front view of a fire tube boiler provided with a modified form of my soot blowing construction.

40 Figure 6 a side view of the end of the boiler and of the soot blowing construction on Fig. 5.

Figure 7, a plan view on the section line 7—7 of Fig. 5.

45 Figure 8 a cross section on the line 8—8 of Fig. 5, and

Figure 9 a section on the line 9—9 of Fig. 5.

Referring first to the construction of Figs. 50 1 and 4, A indicates the head of the boiler, B, B, etc. the fire tubes extending through the boiler and opening through the heads thereof. C, C, are steam pipes connected with the valve casings indicated at D, D. 55 These valve casings, as shown in Fig. 4, are

each provided with a cylindrical seat D' for the plug cock D⁵ with a port D² to which the pipe C is connected and with distributing ports D³ and D⁴, the ends of which are threaded, as indicated at d³ and d⁴ so as to 60 provide a rotatable connection with the steam pipes to be described. D⁵ indicates the rotatable plug valve having a port, as shown, by means of which the port D² can be connected with either outlet, D³ or D⁴.

65 The threaded sockets d³ and d⁴ are located entirely to one side of the group of tubes in connection with which the soot blower frame connected to these sockets is intended to operate. E is a steam pipe rotatably connected with the socket d³ as by being screwed into it and provided with an angularly ex-

70 tends arm E', by means of which it is connected to a tubular soot blower frame made up of a central tube E², to which are connected transversely extending pipes G, G, etc., to which in turn are connected the soot blowing nozzles, indicated at g. F is a

75 rotatable steam conduit screwing into the socket d⁴ and connected by an angularly ex-

80 tends arm F' with the adjacent tubular soot blower frame made up of the main conduit F² and the transversely extending pipes G' to which the soot blower nozzles are in turn connected. By my construction the 85

angular extensions E' and F', by which adjacent soot blower frames are connected to the steam supply, overlap each other and each one of the laterally extending pipes F', as shown, is curved, as indicated at F³, so as 90 to clear the rotatable steam pipe E, as shown, feeding the other tubular soot blowing frame of the pair with steam.

As shown, each frame is provided with a hook like socket, indicated at M, in which, 95 when the frames are in proper operative position, the locking bar M' is engaged so as to prevent the frames from being swung out of position.

When it is desired to have access to any 100 group of tubes the locking device is removed and the soot blower frame covering the group of tubes swung to one side, leaving the tube group entirely exposed.

Referring next to the modified device, as 105 shown in Figs. 5 to 9, the steam supply pipe, here indicated at CC, is connected to a valve head DD, having four outlet ports, indicated at d', d², d³ and d⁴, with which are connected steam conduits indicated at H, H', H² and 110

H^3 , the upper pair of pipes, H , H' , connecting, through angular extensions I , I' , with sockets J , J' , with which, as by a screw connection, the pipes K and L are rotatably connected. The sockets J and J' are each located to one side of the group of tubes with which the connected soot blower frame is to operate and the soot blower frames, which are similar in construction to those already described, are connected with the rotatable pipes K and L by the angular extensions K' and L' which overlap each other and one of which is so formed as to clear the rotatable connection of the other portion 15 of the pair, as, for instance, by being curved, as shown at L^3 Fig. 7, K^2 and L^2 being the central pipes. The pipes H^2 and H^3 connect with the sockets J^2 and J^3 to which in turn are rotatably connected pipes k and l 20 which have angular lapping extensions k' and l' connecting with the central pipes k^2 and l^2 of soot blower frames similar to those already described. It will, of course, be obvious that in this modified construction, 25 as in the one first described, either one of the pair of soot blower frames can be rotated entirely away from in front of the tubes with which it normally operates.

While the described construction in which

the angular extensions of the rotatable steam supply pipes overlap each other has clear advantage it will be obvious that some meritorious features of my invention can be availed of without necessarily involving this feature.

Having now described my invention, what I claim as new and desire to secure by Letters Patent, is:

In combination with a fire tube boiler, a soot blower construction comprising in combination a pair of tubular soot blower frames adapted when in operative position to extend over and lie close to separate groups of tubes, steam pipes rotatably supported at one side of the tubular frames to which they are connected, said rotatable steam pipes having angular extensions respectively connecting with said frame, each of said steam pipes being rotatably supported at one side of the respective frame, said angular extensions overlapping each, and one being so formed as to clear the rotatable pipe having the other extension so as to permit either member of the pair of frames to be swung away from in front of the group of tubes it normally faces.

JOHN PETTY.
